KNITTING MACHINE

Guido O. Clauss, Elizabethtown, Pa.

Application September 21, 1940, Serial No. 357,803

18 Claims. (CL 66—96)

This invention relates to apparatus for making full fashioned hosiery embodying a non-run fabric such as disclosed in my copending application Serial No. 273,813 filed May 15, 1939.

The object of the present invention is to provide mechanism which can be readily applied to existing flat full fashioned hosiery knitting machines, both leggers and footers or single-unit machines which make both leg and foot on one machine, to cooperate with the normal regular mechanism of the machine, and which may be readily rendered inoperative to permit the machine to knit regular normal fabric when desired.

The construction of the new mechanism and its cooperation with the normal elements of the machine will be fully disclosed hereinafter, reference being had to the accompanying drawings of which:

Fig. 1 is a side view of a completed stocking made in accordance with the principles of the present invention;

Fig. 2 illustrates the flat stocking blank before seaming;

Fig. 3 shows a swatch of the non-run fabric, diagrammatically;

Figs. 4 to 10 inclusive illustrate the progression of steps attending the formation of a single non-run course of stitches;

Figs. 11 to 21 inclusive are cross-sectional views through the sinker bed, presser bar and knock-over bar, illustrating the various movements of the needles and stitch-spreading points during the formation of a non-run course and a succeeding course of regular stitches;

Fig. 22 is a transverse sectional elevation of the knitting machine equipped with the new mechanism for making the non-run fabric;

Fig. 23 is a face view of the shogging mechanism for the stitch spreading points as viewed at line 23—23, Fig. 22;

Fig. 24 is a plan view of the mechanism shown in Fig. 23;

Fig. 25 is a section taken on the line 25—25, Fig. 23;

Fig. 26 illustrates an enlargement of the point shogging cam and its associated follower;

Fig. 27 illustrates the throw-out mechanism for the point shogging means, in perspective;

Fig. 28 is a perspective view, partly in section, of the legger machine equipped with non-run mechanism according to the present invention;

Fig. 29 is a perspective view partly in section, of a footer machine equipped with non-run mechanism according to the present invention;

Fig. 30 is a perspective view of the control mechanism for the non-run apparatus as applied to the footer;

Fig. 31 is a transverse sectional view of a detail of the invention showing means for operating covering knives for the narrowing points of the footer;

Fig. 32 is a detail view of the cam for operating the covering knives for the narrowing points of the footer;

Fig. 33 is a face view diagrammatically illustrating mechanism for imparting lateral movement to the covering knives; and

Fig. 34 is a view of the stich cam assembly, for the legger and the footer, including a regular stitch cam, a regular narrowing cam, and a non-run stitch cam.

The stocking A, shown in Fig. 1, and the flat blank, shown in Fig. 2, each include a leg portion A¹ and a foot instep portion A², which are composed of single yarn non-run fabric, and a high splice heel reinforce A³ which is composed of double yarn non-run or plain reinforced fabric.

The stocking and blank of Figs. 1 and 2 respectively, also include foot sole portions B¹, a fashioned toe portion B², heel tabs B³, and a welt or top B⁴ each of which is composed of regular or plain fabric formed of one yarn and reinforced with a second yarn in the usual manner.

The non-run fabric portions A¹, A² and A³ are formed, as illustrated in Fig. 3, with non-run courses a, a, alternating with regular plain courses b, b.

Each non-run course a is composed of locking stitches c, c alternating with regular or plain stitches d, d, while the intermediate plain courses b, b are respectively composed entirely of regular plain stitches e, e.

Each locking stitch c includes a main portion c¹ of substantially the same form as a regular plain stitch, which is formed in one wale and has a laterally extending portion c² spread from the wale of the main body portion c¹ over the plain stitch of the same course but in an adjacent wale, with the laterally spread portion c² twisted at c³ between the two wales. This laterally spread portion c² and the plain stitch d over which it lies are knit together with the next succeeding plain stitch e of the next plain course b in the wale with the stitch d over which the spread portion c² of the locking stitch c lies.

In alternate non-run courses a, the locking stitches c are staggered or offset one wale with respect to the locking stitches of the intermediate non-run course, as shown in Fig. 3. As a result

of this arrangement there is a locking stitch *c* at the intersections of alternate wales and alternate courses, which will effect stopping of runs along each and every wale.

As shown in Fig. 4, alternating locking stitches *c* and plain stitches *d* of a non-run course *a* have been drawn through the stitches *e*, *e* of a previously formed plain course *b*, by the needles *1*, *1*, of the knitting machine.

In Fig. 5, a set of stitch-spreading points *2*, *2* have entered the loops *c* between each of said loops and the beards *3* of the needles on which the loops *c* are hanging, as shown in Fig. 11, and the points *2* have moved rearwardly to carry the bights of the stitch loops *c* back beyond the needle beards *3*, as shown in Figs. 5 and 12.

In Fig. 6 the points *2*, *2*, while still rearwardly spaced from the beards *3*, *3*, have been shogged laterally to the extent of one wale, into planar alignment with the needles respectively adjacent to those on which the loops *c*, *c*, originated. The vertical relation between the fabric *A*¹, the needles *1*, the points *2*, beards *3*, knock-over bits *4*, and sinkers and dividers *5*, while the loop *c* is spread as in Fig. 6, is shown in Fig. 12.

Fig. 7 shows the points *2* as having moved forwardly from the position shown in Fig. 12 to the position shown in Fig. 13, wherein the beards *3* of the needles *1* have entered the grooves *6* in the points *2*, above the spread portion *c*² of the loop *c*. The sinkers and dividers *5*, *5* have also moved forwardly, engaged and bent the spread portion *c*² of the loops *c* to insure entrance of the tips of the needle beards *3* into the spread loop portions *c*² in the manner illustrated in Fig. 14, as the needles are lowered. At this time the sinkers *5* recede and the needles *1* are lowered, with the fabric *A*¹ resting on the tops of the sinkers and dividers *5*, near the forward tips thereof.

With the sinkers and dividers *5* still receding, the needles *1* and points *2* descend and the fabric *A*¹ moves down onto the tops of the knock-over bits *4*, as shown in Fig. 15. The points *2* then rise, as the needles *1* further descend, whereby the points *2* are withdrawn from the spread portions *c*² of the locking loops *c*, as shown in Fig. 16 and in Fig. 8.

When the needles *1*, *1* reach their lowermost position, the spread portions *c*² of the locking loops *c*, which have advanced upwardly along the needle beards *3*, turn over the tops of the needles, as shown in Fig. 17, and produce the twists *c*³ in the spread portions *c*² of the locking loops *c*, as shown in Fig. 9.

The sinkers and dividers *5* then move forward over the fabric *A*¹ lying on the tops of the knock-over bits *4* and the needles *1* rise to move the fabric down on the shanks of the needles *1* to positions below the tips of the beards *3*, in the same manner as in regular narrowing.

The yarn guide *7* (Fig. 18) then traverses the bank of needles *1* and the sinkers and dividers *5* are operated in the usual manner, as shown in Figs. 10 and 18, to sink and divide a new yarn *x* between the adjacent needles *1*, *1*, in the usual manner, for starting a new course *b* of regular plain stitches *e*, *e*.

Figs. 19, 20 and 21 clearly illustrate the new yarn *x* being drawn through the spread portions *c*² of the locking stitches *c* and the underlying plain stitches *d* of the previously formed non-run course *a*, to form the stitches *e*, *e* of the next succeeding course *b* of plain regular stitches *e*, *e*.

During the formation of each course *b* of plain

regular stitches *e* the regular stitch forming mechanism of the knitting machine, including the regular stitch cams, operates in the normal manner.

During the formation of each non-run course *a* composed of the locking stitches *c* alternating with and spread over the intermediate plain or regular stitches *d*, special cams and controls are employed as will be hereinafter described.

During the laying of the new yarn *x* for each non-run course *d* the normal loose course mechanism of the machine is preferably operated to provide greater length to the stitches *c* as originally formed, before spreading, in order to provide enough yarn for the spread portions *c*² of the locking stitches *c* without robbing the main portions *c*¹ of the locking stitches *c*, whereby these main portions *c*¹ will be substantially the same length as the plain stitches *d* in the non-run courses *a* and the plain stitches *e* in the regular courses *b* intermediate the non-run courses *a*, *a*.

As shown in Figs. 22 and 28, the stitch spreading points *2*, *2*, are rigidly secured in laterally spaced relation to each other equal to the distance between two needles *1*, *1*, in a bar *10*. The bar *10* is provided with supporting arms *11*, *11*, which are secured to a horizontal rod *12*. The rod *12* is slidably supported for axial reciprocation in bearings *13*, *13* carried by the shaft *14* of the normal dipping motion of the knitting machine which is supported in the ends of the dipping arms *15*, *15* of the machine. These arms, as usual, are pivotally mounted on the back shaft *16* of the machine.

The dipping of the shaft *14*, and consequently the points *2*, *2*, is effected in the usual manner of regular narrowing, by the dipping cams *17* on the regular cam shaft *20* of the machine, through the usual levers *18* and links *19*.

The lateral shogging of the stitch-spreading points *2*, *2* is produced by any suitable lace tackle with which the knitting machine may be equipped as, for example, the tackle shown in Figs. 22 to 26 inclusive.

In the present instance, the shogging mechanism includes a bracket *21* rigidly secured to the dipping shaft *14*. Pivoted on the bracket *21* is a lever *22* having a forked lower end *23* which straddles the point rod *12* and bears against one side of a collar *24* secured thereto. Between the opposite side of the collar *24* and one of the bearings *13*, which support the point rod *12*, is a spring *25*. This spring tends at all times to move the rod *12* and the spreading points *2*, *2* in one direction axially of said rod, and to rock the shogging lever *22* in a direction to force the cam follower *26* into contact with the periphery of a point shogging cam *27* which is rotatably mounted on the bracket *21*.

The peripheral edge of the shogging cam *27* (Fig. 26) is provided with a plurality of series *y*, *y* of steps *27a*, *27b*, *27c*, with each step formed on a different radius swung from the axis of the cam *27*.

While the step *27a* of the cam *27* is opposite the cam follower *26*, the spreading points *2*, *2* are in planar alignment with the needles *1*, *1*, on which the initial loops of the locking stitches *c*, *c* are hanging, at an elevation wherein the lower tips of the points *2* are above the tops of the needles *1*. The needles *1* move rearwardly in the planes of the points *2* and the points *2* descend and enter the loops *c* hanging on alternate needles *1*, *1*, as shown in Fig. 11. For example,

the points 2, 2 are inserted in the loops of alternate wales z^1, z^1 , as seen in Figs. 3 and 5. The needles 1 and points 2 rise together and the needles move forwardly, while the points 2 and needles 1 are in the same planes. The needles 1 then move forwardly to the position of Fig. 12, to separate the needles from the points.

The cam 27 then moves to bring the step 27b opposite the follower 26, which shifts the points 2, 2, laterally to the left, from the planes of the needles 1, 1 carrying the loops of wales z^1, z^1 , into the planes of the needles carrying the plain loops d, d, in wales z^2, z^2 whereupon the points 2 and needles 1 descend and come together into the position shown in Fig. 13. The points 2, 2 and needles 1, 1 descend together at different speeds, from the position of Fig. 13 through the position of Fig. 14 into the position of Fig. 15. The needles continue to descend into the position of Fig. 16 while the points rise, by which the spread portions c^2 of the locking loops c are stripped from the points 2. The needles 1, 1 then rise through the position shown in Fig. 17 into that of Fig. 18, ready to receive the yarn for the next course b of plain regular stitches.

The needles 1 go through the cycle of Figs. 18, 19, 20 and 21 twice while the intermediate cam step 27b lies opposite the follower 26, i. e. once to form the plain course b and once to form the course of stitches which is to become the next non-run course a. When the loops of the course a are formed, the points 2, 2, which are still in planar alignment with the needles 1 carrying the newly formed loops of wales z^2, z^2 , descend as previously described and enter the newly formed loops of wales z^2, z^2 after which the cam 27 moves to bring the highest step 27c opposite the follower 26, thereby shifting the points 2, 2 to spread the newly formed loops of wales z^2, z^2 over the plain stitches d, d of the next adjacent wales z^1, z^1 , to the left.

During the formation of the next plain course b, the cam 27 is rotated again, to bring one of the lowest steps 27a opposite the follower 26, whereby the points 2, 2 are shogged to the right, out of planar alignment with the needles 1 carrying the stitches of the wales z^1, z^1 across the needles carrying the stitches of the wales z^2, z^2 into planar alignment with the needles carrying the stitches of the wales z^1, z^1 two needles distant from where this later movement of the points 2 to the right began.

The above noted step by step movements of the cam 27 are effected by a ratchet wheel 28 and pawl 29, from the main cam shaft 20 of the machine by a cam 30 on the cam shaft 20 operating against a follower 31 on one end of a lever 32. The lever 32 through a train of links and levers 33, 34, 35, 36, and 37 rocks a lever 38 on which the pawl 29 is pivotally mounted.

At times other than when non-run courses a, a are being produced, during which the cam 30 on the main cam shaft 20 of the machine rotates constantly and would effect undesirable step by step rotating of the point shogging cam 27, the follower 31 may be held out of contact with the cam 30, rendering the point shogging mechanism inoperative, by a latch lever 40 (Figs. 22 and 27) under control of buttons (not shown) on the pattern chain of the machine which is normal to the ordinary knitting machine and therefore has not been shown in the present instance.

The latch lever 40 is shouldered at 41 to lie under the rear end of the lever 32, as shown in Fig. 27. The latch lever 40 is pivoted at 42 to

5 a bracket 43 secured to the rear beam 44 of the knitting machine. The lower end 45 of the latch lever 40 is normally held in contact with a block 46 on a control rod 47 by a spring 48. The control rod 47, is adapted to be reciprocated axially by a lever 50 (Fig. 30) pivoted at 51 to a suitable bracket (not shown) which is secured to the rear beam 44 of the machine.

The upper end 52 of the lever 50 is engaged 10 by a forked end 53 of a rear section 54a of a rod shifting lever 54 which is mounted on a fixed vertical pivot 55 for oscillation in a horizontal plane. The lever 54 includes an intermediate section 54b which is pivoted on a horizontal pivot 15 56 fixed in the rear portion 54a of the shift lever 54. This intermediate section 54b carries a cam follower 57 which is rotatably mounted on a horizontal stud for engagement with the peripheral edge of a disc cam 58 which is secured to the main cam shaft 20 of the knitting machine. The intermediate section 54b also carries a cam follower 59 mounted on a vertical stud fixed in the section 54b, for engagement with a side cam 20 60 on the disc 58 by which the lever 54 is rocked about its pivot 55 to rock the lever 50 and shift the rod 47 to cause the block 46 to rock the latch 40 and release the lever 32, whereby the point shogging cam 27 will be operated step by step when the non-run courses a, a are being formed.

25 As the cam 60 is secured to the main shaft 20 of the knitting machine and rotates constantly therewith it is necessary during such times as plain regular fabric is being knitted to remove the cam follower 59 from the path of the cam 60 and to hold it in such inoperative position. A rise 30 on the peripheral edge of the disc cam 58 functions to rock the intermediate portion 54b of the non-run control lever 54 about its horizontal pivot 56 and thereby lift the cam follower 59 35 above the path of rotation of the side cam 60; and a latch lever 61 engaging the under side of the front end portion 54c of the lever 54 functions to hold the lever portions 54c, 54b and follower 59 in the raised inoperative position. The latch 40 45 61 is controlled by buttons on the normal pattern chain of the knitting machine in the usual manner through a rod 62. The latch 61 is pivoted at 63 to a bracket 64, which is secured to the front beam 65 of the knitting machine.

50 In order to insure the lever 54 being at all times in position to be engaged underneath by the latch 61, the front end section 54c of the lever 54 is pivoted, at its rear end, about a vertical axis 66 fixed in the forward end of the lever section 54b and the front end of the section 54c is forked at 67 to embrace a vertical post 68 secured to and projecting vertically from the bracket 64. When the lever 54 is rocked horizontally by the side cam 60, the front section 54c pivoting about the axis 66 is held within the 55 range of movement of the latch 61 by the forked end 67 embracing the post 68.

60 As previously noted, the vertical movements of the spreading points 2 during spreading of the portions c^2 of the locking stitches c are effected 65 by the dipping cam 17 on the main cam shaft 20. The coordinated vertical movements of the needles 1, 1 are effected by a special cam 70 (Figs. 28, 29 and 34) which is secured to one side of the regular stitch cam 71 on the main cam shaft 20, in the place normally occupied by the regular narrowing cam 12, which latter in the present 70 instance is placed against the non-run cam 70 on the side opposite to the regular stitch cam 71.

75 As usual, the needles 1, 1 are rigidly mounted

in the needle bar 75 which is pivoted at 76 to the rear ends of a pair of levers 77. These levers, as usual, are secured to the stitch shaft 78 on which is also secured a lever 79 with a cam roller 80 rotatably mounted on a stud 81 secured in the lower end of the lever 79.

Normally the roller 80 rides the peripheral edge of the normal stitch cam 71 to produce regular plain stitches and rides the peripheral edge of the narrowing stitch cam 72 only when the cam shaft 20 is shifted axially for narrowing of the fabric.

In the present instance, the cam shaft 20 is shifted axially to its normal extent each time the primary loops of the locking stitches c are to be spread by the points 2, 2. Thus, with the non-run cam 70 immediately adjacent the regular stitch cam 71, the cam roller 80 rides off the regular stitch cam 71 onto the non-run cam 70 each time the cam shaft 20 is shifted to the right as viewed in Figs. 28 and 29, such shifting taking place when the contour portion 82, common to all the cams 70, 71 and 72 is opposite the cam roller 80 (Fig. 34).

As the cam 70 rotates in the direction of the arrow in Fig. 34 and the radii o-f, o-g, o-h, o-i, o-j, o-k, and o-l, successively pass the cam roller 80 the needles 1, 1 are moved into the various elevations shown in Figs. 11, 12, 13, 14, 15, 16, and 17, successively. The cam 17 rotating in unison with the cam 70 at the same time moves the points 2, 2 to the various cooperating elevations, shown in said figures respectively, while the shogging cam 27 moves the points 2 laterally at the proper time in the cycle. At the same time the regular narrowing presser cam (not shown) which is also secured to the main cam shaft 20 and rotates in unison with the cams 70 and 17, rocks the needle bar 75 and consequently the needles 1, 1 through the various angular positions respectively shown in said figures, to cooperate in effecting proper engagement and disengagement between the needles 1 and points 2 to effect proper spreading of the loop portions c² of the locking stitches c.

In addition to being shifted for spreading the locking stitches c, c in the manner above described, the main cam shaft 20 is also shifted in the same manner and to the same extent for narrowing the blank (Fig. 2) at the parts N¹, N², N³, and N⁴. The shifting in each instance is effected by the usual mechanism common to all flat full fashioned hosiery knitting machines, under the control of the usual pattern chain. As this mechanism is of well known construction and operates in a well known manner illustration thereof has been deemed unnecessary in the present instance.

Due to the non-run stitch cam 70 being placed in the normal position of the ordinary narrowing stitch cam 72, i. e. immediately along side of the normal regular stitch cam 71, and due to the narrowing stitch cam 72 being placed immediately along side of the non-run stitch cam 70, it is necessary, when narrowing the blank at the places noted above, to effect a movement of the cam-roller 80 out of the plane of the non-run cam 70 into the plane of the narrowing stitch cam 72. This is accomplished by making the cam roller 80 slidable axially on the stud 81 and by providing means for shifting the roller 80 to the left (Figs. 28 and 29) when the cam shaft 20 shifts to the right, whereby the roller 80, at the spot 82 (Fig. 34), will slide from the plane of the regular stitch cam 71 across the face of the non-

run cam 70 into the plane of the narrowing stitch cam 72, when narrowing is to be effected.

It will be here noted that narrowing takes place in the courses b, b, only and never in a non-run or locking course a, thus it is possible to use the narrowing mechanism for both narrowing and stitch spreading at different times.

The shifting of the cam roller 80 on its supporting stud 81, completely across the non-run stitch cam 70, is effected by a lever 83 (Figs. 28, 29, and 30) which is pivoted at 84 to a bracket 85 secured to the front beam 65 of the knitting machine. The inner end of the lever 83 is forked to receive a block 86 which is pivoted on a vertical pin 87 between the two parts of the forked end of the lever 83. The block 86 is disposed between two collars 88, 88 which are secured to the cam shaft 20.

The outer end 89 of the lever 83 is adapted to be selectively connected to or disconnected from a slideable rod 90 which is mounted in suitable bearings 91 carried by a rigid portion of the machine. Secured to the rod 90 is a guide plate 92 which is provided with a slot 93 for reception of the roller 80, whereby, as the inner end of the lever 83 is rocked to the right, by movement in that direction of the cam shaft 20, the outer end of the lever, the rod 90, the guide plate 92, and the roller 80 will be moved to the left and align the roller 80 with the narrowing stitch cam 72.

The foregoing description applies equally to the mechanism of the legger (Fig. 28) which knits the portion L of the blank (Fig. 2) down to the topping line T-T and the heel tabs B³, B³, and to the footer (Figs. 29 and 30) which knits the lower portion F of the blank.

As shown in Fig. 28 the rod 90, which shifts the roller 80 is connected to the outer end 89 of the lever 83 by a connecting plate 94 which is provided with a slot 95 adapted to embrace a vertical pin 96 on the end 89 of the lever 83 or a fixed locking lug 97 secured to a rigid portion of the knitting machine.

When the blank is being narrowed, the slot 95 of the connecting plate 94 embraces the pin 96 on the lever 83 to effect shifting of the roller 80, but, when non-run fabric is being produced, the connecting plate 94 is swung on the rod 90 to cause the slot 95 to embrace the locking lug 97, whereby the roller 80 is maintained in a fixed position to be engaged by the regular stitch cam 71 for making the plain courses b, or by the non-run stitch cam 70 when the cam shaft 20 is shifted to the right for spreading the loops c² of the locking stitches c during the making of the non-run or locking courses a. In this instance the operation of the connecting plate 94 to and from its above noted positions is effected manually through a handle 98 thereon.

In the case of the footer, as shown in Fig. 29, the rod 90 is automatically connected to and disconnected from the lever 83. In this case (Fig. 30) a block 99 is secured to the rod 90 at one side of and spaced from the lever 83 and a second block 100 is secured to the rod 90 at and closely adjacent to the opposite side of the lever 83. A lever 101 is disposed between the block 99 and the lever 83, with the outer face of the lever 101 in the same plane as the outer face of the block 99. The lever 101 normally lies in contact with the block 99 so that the said flush outer faces together form a continuous surface against and across which the tip 102 of a pawl 103 is adapted to slide. The pawl 103 is pivoted on the outer end 89 of the lever 83. The lever 101 is secured

to a transversely extending rock shaft 104 which has bearing in the bracket 85 on the front beam 65 and in the back beam 44. Adjacent the back beam 44, the shaft 104 is provided with a lever 105 which has its upper end disposed between two collar plates 106 on the control rod 47, whereby, when the control rod 47 is operated by a button on the pattern chain of the machine at the start of a narrowing cycle of the machine the lever 101 will be rocked away from the block 99, leaving the tip 102 of the pawl 103 fall in and engage the end 99a of the block 99, when and as the lever 83 is rocked by the cam shaft 20 shifting to the right (Fig. 29). This causes the pawl 102 to move the block 99, and consequently the rod 90, to the left, which shifts the roller 80 from the plane of the regular stitch cam 71 across the face of the non-run stitch cam 70 into the plane of the narrowing stitch cam 72.

As the lever 83 rocks in the opposite direction, at the end of the narrowing cycle, and as a result of the cam shaft 20 moving to the left, the lever 83 engages the block 100 on the rod 47 and returns the roller 80 to its normal position in the plane of the regular stitch cam 71. At the same time, the rod 47 shifts in an opposite direction and causes the lever 101 to return to its normal position against the end 99a of the block 99, thereby forcing the tip 102 of the pawl 103 away from the block 99 and disconnecting the rod 90 from the lever 83.

During the narrowing operation, on both the footer and the legger, it is essential that the spreading points 2, 2 do not engage the needles 1, 1 at the time the narrowing points 110 engage the needles 1, 1 adjacent the opposite marginal edges respectively of the blank, and for this purpose the bar 10 on which the spreading points 2, 2 are carried is rocked outwardly beyond the plane of the needles 1. This is accomplished by a lever 111 secured to the point shaft 12 (Fig. 29). The lever 111 has a laterally projecting pin 112 adapted to engage a cam surface 113 on a cam lever 114, as the narrowing frame dips by operation of the lever 18 under control of the dipping cam 17.

Normally the cam lever 114 lies to one side and out of the path of the pin 112 during knitting of non-run fabric, but when narrowing is taking place the lever 114 is swung about its pivot 115 by a throw-out lever 116 in opposition to a spring 117 which tends at all times to hold the cam lever 114 out of the path of the throw-out pin 112.

The throw-out lever 116 is secured to a transverse shaft 117 which latter is provided with an arm 118. The arm 118 lies between the arms of a fork 119 which is secured to rod 90. When the rod 90 is shifted to the left (Fig. 29) to move the follower 88 onto the narrowing stitch cam 72, the throw-out shaft 117 is rocked and through the lever 116 moves the throw-out cam 113 into the path of the pin 112 on the lever 111, whereby, when the narrowing frame which carries the point shaft 12 dips, the shaft 12 is rocked and swings the spreading points 2, 2 out beyond the plane of the needle 1, 1 so that these points do not disturb the stitches hanging on the needles 1, 1, intermediate those with which the narrowing points 110, 110 are cooperating to narrow the fabric.

In order to provide what is known as the "cradle foot," wherein the inner marginal edges A^3 of the high splice reinforce A^3 and b^1 and b^2 of the foot sole and toe reinforce B^1 and B^2 are

stepped gradually inwardly and lie at angles to the wales, covering knives 120, 121 are employed (Fig. 29). In the present instance these knives are shown only on the footer but it will be understood that when the non-run fabric is not to extend into the high splice heel reinforce A^3 these knives 120, 121 are also applied to the legger.

As shown in Fig. 29, the covering knives 120 and 121 are carried by arms 122 and 123 respectively. These arms are secured to shift rods 124 and 125 respectively. The rods 124, 125 are slidably mounted in brackets 126 which are secured to the dip shaft 14. These shift rods 124, 125 are secured to stop engaging brackets 127, 128 respectively (Fig. 33). The stop brackets are provided with bearing surfaces 129, 130 which engage bearing surfaces 131 and 132 respectively on stop nuts 133, 134. The stop nuts 133, 134 are threaded on right and left hand portions 135, 136 of a screw 137 which is rotatably mounted in a suitable frame which is fixed rigidly to the main frame of the knitting machine in the usual manner of cradle foot attachments.

The screw 137 is provided with right and left ratchet wheels 138a, 138b which are rotated step by step in opposite directions by a double pawl 139 which is pivoted on an arm 140. The arm 140 is freely rotatable on the screw 137 and is connected by a link 141 to a lever 142 (Fig. 30) having a roller 143 which rides on a cam 144 secured to the main cam shaft 20 of the machine.

During the knitting of the part of the foot adjacent the line T—T (Fig. 2) when the stitches of a locking course a are being spread, the blades 120, 121 cover the narrowing points 110, 110 and the spreading points 2, 2 lying adjacent thereto, so that the covered points will not enter the stitches on the needles normally engaged by the covered points. The covering knives are moved outwardly, in opposite directions, step by step to form the angular edges b^1 , b^1 as the locking courses a , a are successively produced, by turning the screw 137 in one direction step by step.

During the knitting of that part of the foot which includes the inner marginal edges b^2 , b^2 , the screw 137 is rotated in the opposite direction, step by step, merely by manually throwing the pawl 139 out of mesh with one ratchet wheel 138a or 138b, as the case may be, into engagement with the other of said ratchet wheels.

During the knitting of the intermediate portion of the foot, where the inner marginal edges b^3 , b^3 (Fig. 2) of the foot-reinforce B^1 , B^1 are parallel to the wales, the follower 143 on the rocking lever 142 is held out of engagement with the racking cam 144, by a latch 145 (Fig. 30) which is controlled by buttons on the pattern chain of the machine through a control rod 146.

During the knitting of each narrowing course b in the portions N^3 (Fig. 2) the covering knives 120, 121 are thrown out of action by rocking the shafts 124 and 125 to which these knives are respectively connected. For this purpose the rod 124 is provided with a lever 147 (Figs. 29 and 31) which is pivotally connected at 148 to a link 149. The link 149 has a sliding motion through the head of the pivot 148 and a collar 150, secured to said link, is adapted to engage said head and effect rocking of the lever 147.

The slide rod 125 has a pair of levers 151, 151 secured thereto in spaced relation with a roller 152 rotatably mounted on a shaft 153 between said levers, with the opposite ends of the shaft 75 153 secured in said levers respectively. The roller

152 rests against the lever 147 and when this latter lever is rocked it in turn rocks the levers 151, 151 and the slide rod 125. This arrangement is effective to permit relative sliding motion between the two slide rods 124, 125 while using a single actuating link 149 to effect simultaneous rocking of the two rods and their respective covering knives 120, 121.

The lower end of the link 149 (Fig. 30) is pivotally connected to a lever 154 which carries a follower stud 155. A follower 156 is rotatably and slidably mounted on the stud 155. Normally this follower rides a substantially circular disc 157 and holds the knives 120, 121 in an inoperative position, during knitting of regular courses b, b of plain stitches, e. e.

When the cam shaft 20 shifts to effect spreading of the locking stitches c, c, the cam follower 156 rides a cam 158 by which the knives 120, 121 are brought into operative relation to the narrowing points 110, 110 and the adjacent spreading points 2, 2 and are held there during the spreading operation, later returning to the inoperative position preparatory to the cam shaft 20 shifting in the opposite direction for knitting a new course of stitches.

When the cam shaft 20 shifts for narrowing in the parts N³ (Fig. 2) and the rod 47 is also shifted, by the lever 54, the follower 156 moves off the disc 157 and completely across the cam 158 onto another cam 159, which actuates the knives 120, 121 into operative engagement with the points 110, 110 and 2, 2, returning the knives to their inoperative position after the narrowing operation is completed. At the same time, however, the cam 113 becomes effective to move the spreading points 2, 2 out of alignment with the needles 1, 1. This causes the knives 120, 121 to be moved away from the narrowing points 110, 110 which at this time are under control of the regular narrowing mechanism of the machine. But, when the narrowing of the toe portion N⁴ is taking place the spreading points 2, 2 are permanently removed from alignment with the needles 1, 1, while the knives 120, 121 are outside the opposite ends of the point bar 10, thus leaving the knives 120, 121 free to operate in the normal manner during the knitting of the box toe B², at which time the center covering knife 160 also comes into operation in the normal usual manner.

The shifting of the follower 156 onto the cam 159, as above noted, is effected by a lever 161 (Fig. 30) which is slotted at 162 to embrace and guide the follower 156. The lever 161 is pivoted at 163 to a fixed part of the machine and has its second end 164 positioned between blocks or collars 165, 165 on the rod 47, so that, when the rod 47 shifts for narrowing, the follower 156 will be moved onto the cam 159.

The comb formed of the bar 10 and spreading points 2, 2 is held in and out of action by a collar 166 secured to the point rod 12 and having two flats 167, 168 with a point 169 therebetween, and a flat spring 170 which is carried by a collar 171 secured to the dip shaft 14.

Normally the flat 167, bearing against the flat spring 170, holds the points 2, 2 in position to cooperate with the needles 1, 1. During narrowing, when the cam 113 engages the pin 112 and rocks the points 2, 2 out of needle alignment, the point 169 bearing against the flat spring 170 tends at all times to return the points 2, 2 to needle alignment. When the points 2, 2 are to be permanently held out of needle alignment the

point shaft 12 will be turned until the flat 168 bears against the spring 170.

From the foregoing description it will be clear that by employing the mechanism herein disclosed, together with the usual and ordinary parts of any of the well known full fashioned hosiery knitting machines, for example the "Reading" machine, legger and footer, it is possible to knit a stocking of the type shown in Figs. 1 and 2, 10 wherein the leg A¹ and instep A² are composed of non-run fabric, with the welt B⁴, heel tabs B³, toe B², sole B¹, and if desired the high splice heel reinforce A³, composed of plain reinforced fabric with the inner marginal edges of the plain 15 reinforced area of the foot etc., either parallel or at angles to the wales in what is known as a French heel or a cradle foot; and that when non-run fabric is not desired the machine may be operated to produce plain fabric at will and without necessitating the removal of the non-run attachments of the present invention.

I claim:

1. In non-run mechanism for a conventional full fashioned hosiery knitting machine having 25 a bank of needles, a cam shaft, a plain stitch cam and a narrowing stitch cam secured to said shaft, a lever and cam follower common to said plain and narrowing stitch cams for operating said needles, means for axially shifting said cam 30 shaft to a normal extent to effect selective alignment of one of said stitch cams with said common follower, pattern means for controlling said shaft shifting means, narrowing points cooperative with said needles to effect transfer of stitches 35 from needle to needle of said bank, and means including a cam on said shaft for operating said narrowing points vertically in conjunction with operations of said needles by said narrowing stitch cam to effect said stitch transfer, the combination 40 of a series of stitch spreading points for spreading stitches on predetermined needles over needles respectively adjacent thereto, a non-run stitch cam secured to said shaft between said plain stitch cam and said narrowing stitch cam in the normal position of said narrowing stitch cam 45 relative to said plain stitch cam and engageable with said common follower to effect cooperative action of said needles with said spreading points when said cam shaft is shifted to said normal extent.
2. In non-run mechanism for a conventional full fashioned hosiery knitting machine having 55 a bank of needles, a cam shaft, a plain stitch cam and a narrowing stitch cam secured to said shaft, a lever and cam follower common to said plain and narrowing stitch cams for operating said needles, means for axially shifting said cam shaft to a normal extent to effect selective alignment of one of said stitch cams with said common follower, pattern means for controlling said shaft shifting means, narrowing points cooperative 60 with said needles to effect transfer of stitches from needle to needle of said bank, means including a cam on said shaft for operating said narrowing points vertically in conjunction with operations of said needles by said narrowing stitch cam to effect said stitch transfer, the combination 65 of a series of stitch spreading points for spreading stitches on predetermined needles over needles respectively adjacent thereto, a non-run stitch cam secured to said shaft between said plain stitch cam and said narrowing stitch cam in the normal position of said narrowing stitch cam 70 relative to said plain stitch cam and engageable with said common follower to effect cooperative

ative action of said needles with said spreading points when said cam shaft is shifted to said normal extent, and means operable by said normal shifting of said cam shaft for shifting said common follower from said plain stitch cam across said non-run stitch cam onto said narrowing stitch cam.

3. In non-run mechanism for a conventional full fashioned hosiery knitting machine having a bank of needles, a cam shaft, a plain stitch cam and a narrowing stitch cam secured to said shaft, a lever and cam follower common to said plain and narrowing stitch cams for operating said needles, means for axially shifting said cam shaft to a normal extent to effect selective alignment of one of said stitch cams with said common follower, pattern means for controlling said shaft shifting means, narrowing points cooperative with said needles to effect transfer of stitches from needle to needle of said bank, and means including a cam on said shaft for operating said narrowing points vertically in conjunction with operations of said needles by said narrowing stitch cam to effect said stitch transfer, the combination of a series of stitch spreading points for spreading stitches on predetermined needles over needles respectively adjacent thereto, a non-run stitch cam secured to said shaft between said plain stitch cam and said narrowing stitch cam in the normal position of said narrowing stitch cam relative to said plain stitch cam and engageable with said common follower to effect cooperative action of said needles with said spreading points when said cam shaft is shifted to said normal extent, means operable by said normal shifting of said cam shaft for shifting said common follower from said plain stitch cam across said non-run stitch cam onto said narrowing stitch cam, and means for selectively rendering said follower shifting means inactive during said normal shifting of said cam shaft.

4. In non-run mechanism for a conventional full fashioned hosiery knitting machine having a bank of needles, a cam shaft, a plain stitch cam and a narrowing stitch cam secured to said shaft, a lever and cam follower common to said plain and narrowing stitch cams for operating said needles, means for axially shifting said cam shaft to a normal extent to effect selective alignment of one of said stitch cams with said common follower, pattern means for controlling said shaft shifting means, narrowing points cooperative with said needles to effect transfer of stitches from needle to needle of said bank, and means including a cam on said shaft for operating said narrowing points vertically in conjunction with operations of said needles by said narrowing stitch cam to effect said stitch transfer, the combination of a series of stitch spreading points for spreading stitches on predetermined needles over needles respectively adjacent thereto, a non-run stitch cam secured to said shaft between said plain stitch cam and said narrowing stitch cam in the normal position of said narrowing stitch cam relative to said plain stitch cam and engageable with said common follower to effect cooperative action of said needles with said spreading points when said cam shaft is shifted to said normal extent, means operable by said normal shifting of said cam shaft for shifting said common follower from said plain stitch cam across said non-run stitch cam onto said narrowing stitch cam, means for selectively rendering said follower shifting means inactive during said normal shifting of said cam shaft, and means adapted

to cooperate with said follower shifting means for locking said follower in one position for selective engagement with said plain and non-run stitch cams.

5. In non-run mechanism for a conventional full fashioned hosiery knitting machine having a bank of needles, a cam shaft, a plain stitch cam and a narrowing stitch cam secured to said shaft, a lever and cam follower common to said plain and narrowing stitch cams for operating said needles, means for axially shifting said cam shaft to a normal extent to effect selective alignment of one of said stitch cams with said common follower, pattern means for controlling said shaft shifting means, narrowing points cooperative with said needles to effect transfer of stitches from needle to needle of said bank, and means including a cam on said shaft for operating said narrowing points vertically in conjunction with operations of said needles by said narrowing stitch cam to effect said stitch transfer, the combination of a series of stitch spreading points for spreading stitches on predetermined needles over needles respectively adjacent thereto, a non-run stitch cam secured to said shaft between said plain stitch cam and said narrowing stitch cam in the normal position of said narrowing stitch cam relative to said plain stitch cam and engageable with said common follower to effect cooperative action of said needles with said spreading points when said cam shaft is shifted to said normal extent, means operable by said normal shifting of said cam shaft for shifting said common follower from said plain stitch cam across said non-run stitch cam onto said narrowing stitch cam, and means operable by said pattern means for rendering said follower shifting means inoperative during normal shifting of said cam shaft.

6. In non-run mechanism for a conventional full fashioned hosiery knitting machine having a bank of needles, a cam shaft, a plain stitch cam and a narrowing stitch cam secured to said shaft, a lever and cam follower common to said plain and narrowing stitch cams for operating said needles, means for axially shifting said cam shaft to a normal extent to effect selective alignment of one of said stitch cams with said common follower, pattern means for controlling said shaft shifting means, narrowing points cooperative with said needles to effect transfer of stitches from needle to needle of said bank, and means including a cam on said shaft for operating said narrowing points vertically in conjunction with operations of said needles by said narrowing stitch cam to effect said stitch transfer, the combination of a series of stitch spreading points for spreading stitches on predetermined needles over needles respectively adjacent thereto, a non-run stitch cam secured to said shaft between said plain stitch cam and said narrowing stitch cam in the normal position of said narrowing stitch cam relative to said plain stitch cam and engageable with said common follower to effect cooperative action of said needles with said spreading points when said cam shaft is shifted to said normal extent, means for shifting said spreading points laterally from needle to needle including a cam, a ratchet wheel secured to the cam, a pawl for moving the ratchet wheel and cam step by step to effect shifting of said spreading points, a lever for actuating said pawl, and a cam on said cam shaft for operating said lever when said cam shaft is shifted to said normal extent

7. In non-run mechanism for a conventional

full fashioned hosiery knitting machine having a bank of needles, a cam shaft, a plain stitch cam and a narrowing stitch cam secured to said shaft, a lever and cam follower common to said plain and narrowing stitch cams for operating said needles, means for axially shifting said cam shaft to a normal extent to effect selective alignment of one of said stitch cams with said common follower, pattern means for controlling said shaft shifting means, narrowing points cooperative with said needles to effect transfer of stitches from needle to needle of said bank, and means including a cam on said shaft for operating said narrowing points vertically in conjunction with operations of said needles by said narrowing stitch cam to effect said stitch transfer, the combination of a series of stitch spreading points for spreading stitches on predetermined needles over needles respectively adjacent thereto, a non-run stitch cam secured to said shaft between said plain stitch cam and said narrowing stitch cam in the normal position of said narrowing stitch cam relative to said plain stitch cam and engageable with said common follower to effect cooperative action of said needles with said spreading points when said cam shaft is shifted to said normal extent, means operable by said normal shifting of said cam shaft for shifting said common follower from said plain stitch cam across said non-run stitch cam onto said narrowing stitch cam, means for shifting said spreading points laterally from needle to needle including a cam, a ratchet wheel secured to the cam, a pawl for moving the ratchet wheel and cam step by step to effect shifting of said spreading points, a lever for actuating said pawl, a cam on said cam shaft for operating said lever when said cam shaft is shifted to said normal extent, and means for rendering said lever inactive when said common follower shifting means is active.

8. In non-run mechanism for a conventional full fashioned hosiery knitting machine having a bank of needles, a cam shaft, a plain stitch cam and a narrowing stitch cam secured to said shaft, a lever and cam follower common to said plain and narrowing stitch cams for operating said needles, means for axially shifting said cam shaft to a normal extent to effect selective alignment of one of said stitch cams with said common follower, pattern means for controlling said shaft shifting means, narrowing points cooperative with said needles to effect transfer of stitches from needle to needle of said bank, means including a cam on said shaft for operating said narrowing points vertically in conjunction with operations of said needles by said narrowing stitch cam to effect said stitch transfer, covering knives cooperating with said points to render predetermined points ineffective, and means for moving said knives into and out of effective relation to said points as a body including an idler cam and a narrowing cam on said cam shaft, a lever carrying a follower engageable selectively with said cams, the combination of a series of stitch spreading points for spreading stitches on predetermined needles over needles respectively adjacent thereto, a non-run stitch cam secured to said shaft between said plain stitch cam and said narrowing stitch cam in the normal position of said narrowing stitch cam relative to said plain stitch cam and engageable with said common follower to effect cooperative action of said needles with said spreading points when said cam shaft is shifted to said normal extent, a third cam on said cam shaft between the idler and narrowing cams for operating said covering knives into and out of engagement with said narrowing and stitch spreading points when said cam shaft is shifted to said normal extent, means for moving said knives laterally to vary the number of stitch spreading points to be rendered ineffective thereby, and means for rendering said covering knife controlling cam follower from said idler cam across said third cam onto said narrowing cam during said normal shifting of said cam shaft.

5 extent, a third cam on said cam shaft between the idler and narrowing cams for operating said covering knives into and out of engagement with said narrowing and stitch spreading points when said cam shaft is shifted to said normal extent, and means for moving said knives laterally to vary the number of stitch spreading points to be rendered ineffective thereby.

9. In non-run mechanism for a conventional full fashioned hosiery knitting machine having a bank of needles, a cam shaft, a plain stitch cam and a narrowing stitch cam secured to said shaft, a lever and cam follower common to said plain and narrowing stitch cams for operating said needles, means for axially shifting said cam shaft to a normal extent to effect selective alignment of one of said stitch cams with said common follower, pattern means for controlling said shaft shifting means, narrowing points cooperative with said needles to effect transfer of stitches from needle to needle of said bank, means including a cam on said shaft for operating said narrowing points vertically in conjunction with operations of said needles by said narrowing stitch cam to effect said stitch transfer, covering knives cooperating with said points to render predetermined points ineffective, and means for moving said knives into and out of effective relation to said points as a body including an idler cam and a narrowing cam on said cam shaft, and a lever carrying a follower engageable selectively with said cams, the combination of a series of stitch spreading points for spreading stitches on predetermined needles over needles respectively adjacent thereto, a non-run stitch cam secured to said shaft between said plain stitch cam and said narrowing stitch cam in the normal position of said narrowing stitch cam relative to said plain stitch cam and engageable with said common follower to effect cooperative action of said needles with said spreading points when said cam shaft is shifted to said normal extent, a third cam on said cam shaft between the idler and narrowing cams for operating said covering knives into and out of engagement with said narrowing and stitch spreading points when said cam shaft is shifted to said normal extent, means for moving said knives laterally to vary the number of stitch spreading points to be rendered ineffective thereby, and means for shifting said covering knife controlling cam follower from said idler cam across said third cam onto said narrowing cam during said normal shifting of said cam shaft.

10. In non-run mechanism for a conventional full fashioned hosiery knitting machine having a bank of needles, a cam shaft, a plain stitch cam and a narrowing stitch cam secured to said shaft, a lever and cam follower common to said plain and narrowing stitch cams for operating said needles, means for axially shifting said cam shaft to a normal extent to effect selective alignment of one of said stitch cams with said common follower, pattern means for controlling said shaft shifting means, narrowing points cooperative with said needles to effect transfer of stitches from needle to needle of said bank, means including a cam on said shaft for operating said narrowing points vertically in conjunction with operations of said needles by said narrowing stitch cam to effect said stitch transfer, covering knives cooperating with said points to render predetermined points ineffective, and means for moving said knives into and out of effective relation to said points as a body including an idler

cam and a narrowing cam on said cam shaft, and a lever carrying a follower engageable selectively with said cams, the combination of a series of stitch spreading points for spreading stitches on predetermined needles over needles respectively adjacent thereto, a non-run stitch cam secured to said shaft between said plain stitch cam and said narrowing stitch cam in the normal position of said narrowing stitch cam relative to said plain stitch cam and engageable with said common follower to effect cooperative action of said needles with said spreading points when said cam shaft is shifted to said normal extent, a third cam on said cam shaft between the idler and narrowing cams for operating said covering knives into and out of engagement with said narrowing and stitch spreading points when said cam shaft is shifted to said normal extent, means for moving said knives laterally to vary the number of stitch spreading points to be rendered ineffective thereby, means for shifting said covering knife controlling cam follower from said idler cam across said third cam onto said narrowing cam during said normal shifting of said cam shaft, and means for swinging said stitch spreading points as a body out of vertical alignment with said needles during vertical movement of said narrowing points.

11. In non-run mechanism for a conventional full fashioned hosiery knitting machine having a bank of needles, a cam shaft, a plain stitch cam and a narrowing stitch cam secured to said shaft, a lever and cam follower common to said plain and narrowing stitch cams for operating said needles, means for axially shifting said cam shaft to a normal extent to effect selective alignment of one of said stitch cams with said common follower, pattern means for controlling said shaft shifting means, narrowing points cooperative with said needles to effect transfer of stitches from needle to needle of said bank, means including a cam on said shaft for operating said narrowing points vertically in conjunction with operations of said needles by said narrowing stitch cam to effect said stitch transfer, covering knives cooperating with said points to render predetermined points ineffective, and means for moving said knives into and out of effective relation to said points as a body including an idler cam and a narrowing cam on said cam shaft, and a lever carrying a follower engageable selectively with said cams, the combination of a series of stitch spreading points for spreading stitches on predetermined needles over needles respectively adjacent thereto, a non-run stitch cam secured to said shaft between said plain stitch cam and said narrowing stitch cam in the normal position of said narrowing stitch cam relative to said plain stitch cam and engageable with said common follower to effect cooperative action of said needles with said spreading points when said cam shaft is shifted to said normal extent, a third cam on said cam shaft between the idler and narrowing cams for operating said covering knives into and out of engagement with said narrowing and stitch spreading points when said cam shaft is shifted to said normal extent, means for moving said knives laterally to vary the number of stitch spreading points to be rendered ineffective thereby, means for shifting said covering knife controlling cam follower from said idler cam across said third cam onto said narrowing cam during said normal shifting of said cam shaft, and means for swinging said stitch spreading points as a body out of vertical alignment with

said needles during vertical movement of said narrowing points, and means for rendering the lateral shifting means for said covering knives inoperative.

12. In non-run mechanism for a conventional full fashioned hosiery knitting machine as described, the combination of a comb comprising a series of stitch spreading points spaced apart equally to multiples of the spacing of the needles of the machine, a rod carrying said comb, a rotary cam for imparting axial movement to said rod and consequent lateral shifting of said points, said cam comprising high, intermediate and low steps constituting a cycle of operations of said points from respective alignment with one series of predetermined needles into alignment with needles of a second series lying respectively adjacent the needles of the first series, from alignment with the needles of the second series into alignment with needles of a third series lying respectively adjacent the needles of the second series, and from alignment with the needles of the third series into alignment with the needles of the first series for a repeat of the cycle, means for rotating said point shifting cam step by step to produce said cycle including a racking cam on the main cam shaft of the machine, a lever rocked by said racking cam, pawl and ratchet mechanism operable by said rocking lever, and a latch engageable with said rocking lever to render said step cam inoperative.

13. In non-run mechanism for a conventional full fashioned hosiery knitting machine as described, the combination of a comb comprising a series of stitch spreading points spaced apart equally to multiples of the spacing of the needles of the machine, a rod carrying said comb, a rotary cam for imparting axial movement to said rod and consequent lateral shifting of said points, said cam comprising high, intermediate and low steps constituting a cycle of operations of said points from respective alignment with one series of predetermined needles into alignment with needles of a second series lying respectively adjacent the needles of the first series, from alignment with the needles of the second series into alignment with needles of a third series lying respectively adjacent the needles of the second series, and from alignment with the needles of the third series into alignment with the needles of the first series for a repeat of the cycle, means for rotating said point shifting cam step by step to produce said cycle, means for rendering said step cam inoperative, means for swinging said comb about the axis of said rod to remove said points from alignment with all said needles comprising an arm secured to said rod, a pin projecting laterally from said arm, and a cam engageable with said pin to effect said swinging of said points.

14. In a device of the type described, the combination of a bank of knitting needles, a series of stitch spreading points cooperative with predetermined needles, an axially shiftable cam shaft, a plain stitch cam, a non-run stitch cam, and a narrowing stitch cam side by side on said cam shaft, a needle operating lever and a cam follower thereon normally engageable with said plain stitch cam and adapted to engage said non-run stitch cam upon axial shifting of said cam shaft, and means for shifting said follower relative to said lever from said non-run cam onto said narrowing cam.

15. In a device of the type described, the combination of a bank of knitting needles, a series

of stitch spreading points cooperative with pre-determined needles, an axially shiftable cam shaft, a plain stitch cam, a non-run stitch cam, and a narrowing stitch cam side by side on said cam shaft, a needle operating lever and a cam follower thereon normally engageable with said plain stitch cam and adapted to engage said non-run stitch cam upon axial shifting of said cam shaft, and means for shifting said follower relative to said lever from said non-run cam onto said narrowing cam comprising a control rod, a fork on said control rod embracing said follower, a lever having one end connected to said cam shaft and its second end adjacent said rod, and means for connecting said second end to said rod.

16. In a device of the type described, the combination of a bank of knitting needles, a series of stitch spreading points cooperative with pre-determined needles, an axially shiftable cam shaft, a plain stitch cam, a non-run stitch cam, and a narrowing stitch cam side by side on said cam shaft, a needle operating lever and a cam follower thereon normally engageable with said plain stitch cam and adapted to engage said non-run stitch cam upon axial shifting of said cam shaft, means for shifting said follower relative to said lever from said non-run cam onto said narrowing cam comprising a control rod, a fork on said control rod embracing said follower, a lever having one end connected to said cam shaft and its second end adjacent said rod, and means for connecting said second end to said rod, and means for rendering said connecting means inoperative.

17. In a device of the type described, the combination of a bank of knitting needles, a series of stitch spreading points cooperative with pre-determined needles, an axially shiftable cam shaft, a plain stitch cam, a non-run stitch cam, and a narrowing stitch cam side by side on said cam shaft, a needle operating lever and a cam follower thereon normally engageable with said plain stitch cam and adapted to engage said non-run stitch cam upon axial shifting of said cam shaft, means for shifting said follower relative to said lever from said non-run cam onto

5 said narrowing cam comprising a control rod a fork on said rod embracing said follower, a rod actuating lever having one end connected to said cam shaft and its second end adjacent said rod, a block on said rod, a pawl on the second end of said actuating lever engageable with one end of said block to operate said rod, a pawl throw-out lever adapted to abut the pawl engaging end of said block with the outer faces of said block and said throw-out lever flush for holding the pawl inoperative with respect to the block, and means for rocking the throw-out lever away from the block to permit engagement of the pawl with said end of said block.

10 18. In a device of the type described, the combination of a bank of knitting needles, a series of stitch spreading points cooperative with pre-determined needles, an axially shiftable cam shaft, a plain stitch cam, a non-run stitch cam, and a narrowing stitch cam side by side on said cam shaft, a needle operating lever and a cam follower thereon normally engageable with said plain stitch cam and adapted to engage said non-run stitch cam upon axial shifting of said cam shaft, means for shifting said follower relative to said lever from said non-run cam onto said narrowing cam comprising a control rod, an actuating lever for said control rod with one end connected to said main cam shaft, means operably connecting the second end of said lever to said control rod, and a throw-out lever for said connecting means, a second control rod for actuating said throw-out lever, an operating lever for said second control rod, means operatively connecting one end of said operating lever to said second control rod, a cam follower on the second end of said operating lever, a cam on said cam shaft for rocking said operating lever to operate said second control rod, a second cam follower on said operating lever operating against a cam on said cam shaft for releasing the first said follower from its operating cam, and a latch for holding said second cam follower away from its operating cam to render said throw-out lever inoperative.
